DESIGN FOR A COMBINED TOP, BACK SPLASHER, AND ACCESSORY UNITS FOR RANGES

Alfons Barnsteiner, Mansfield, Ohio, assignor to Westinghouse Electric & Manufacturing Company, a corporation of Pennsylvania

Application December 13, 1939, Serial No. 88,852

Term of patent 7 years

To all whom it may concern:

Be it known that I, Alfons Barnsteiner, a citizen of the United States, residing at Mansfield, in the county of Richland and State of Ohio, have invented a new, original, and ornamental Design for a Combined Top, Back Splasher, and Accessory Units for Ranges, of which the following is a specification, reference being had to the accompanying drawing, forming part thereof, in which:

Fig. 1 is a view in perspective showing the top and front of a combined top, back splasher and accessory units for ranges embodying my new design;

Fig. 2 is a view in perspective showing the top, front and right side thereof; and

Fig. 3 is a detailed front elevational view on a slightly enlarged scale of the panel on which the signal elements are shown in Figs. 1 and 2.

The dominant features of my design reside in the portions shown in full lines.

I claim:

The ornamental design for a combined top, back splasher, and accessory units for ranges, substantially as shown and described.

ALFONS BARNSTEINER.
